C. H. RUTTER

COMBINATION TOOL

Filed Oct. 27, 1926

Inventor:

Clark H. Rutter,

Robert D. Andelle,

Attorney.

Patented Apr. 24, 1928.

1,666,977

UNITED STATES PATENT OFFICE.

CLARK H. RUTTER, OF NEW CASTLE, PENNSYLVANIA.

COMBINATION TOOL.

Application filed October 27, 1926. Serial No. 144,428.

The object of my present invention, broadly speaking, is to provide a combination tool which is simple in its construction, positive in its actions, easily manipulated in practice, economical in use, and which can be manufactured and sold at a comparatively low price.

More specifically stated, my object is to provide a tool especially intended to be employed in connection with framing pictures or the like to provide means for trimming off the edges of the backing or sealing paper which has previously been pasted over the back of the frame, for forming holes in the frame for starting screw-eyes, and for turning the screw-eyes securely into their final position in said holes.

Other objects and particular advantages of my invention will suggest themselves in the course of the following description, and that which is new will be brought out in the appended claim.

The preferred means for carrying out the principles of my invention in a practical, efficient, and mechanically correct manner, is shown in the accompanying drawings, in which—Fig. 1 is a perspective view of my invention, as it would appear in actual practice as performing one of its operations; Fig. 2 is a plan view of the body member, opened out flat, before it is bent into final shape; Fig. 3 shows the stem portion alone; Fig. 4 is a perspective view of the complete device; Fig. 5 is a side elevation of the complete device, showing the side opposite to that shown in Fig. 4; Fig. 6 is a cross-section of the device, as taken on the line 6—6 of Fig. 5; Fig. 7 is a perspective view of the clamping thimble alone; and Fig. 8 is a front edge-view of my device.

Similar indices denote like parts throughout the several views.

In order that the construction, the operation, and the several advantages of the invention may be more fully understood and appreciated, I will now take up a detailed description thereof, in which I will set forth the same as comprehensively as I may.

In the drawings letter A denotes a portion of a picture frame or the like, B denotes a sheet of paper which is pasted over the back of the frame, C denotes surplus paper which extends out over the edges of said frame, D denotes the surplus paper which has been cut from the sheet B by my tool, and E denotes a human hand as grasp-

ing my tool to perform the cutting operation.

The invention proper includes the body portion which consists of sheet metal cut into substantially the form shown in Fig. 2, and it comprises the two side portions 1 and 2, and a central portion 3. Formed on the opposite edges of the sides 1 and 2 are the respective taper portions or flanges 4 and 5.

Extending from the outer (rear) corner of the side 1 is a tongue 6 which forms a guide, as will hereinafter be further explained.

Also extending out from the edge of the side 1 is a tooth 7, the same being located near the smaller end of the flange 4.

Extending out from the forward end of the side 1 is a tooth 8.

Extending from the rear corner of the side 2 is a tongue 9.

Formed between the tongue 9 and the larger end of the flange 5 is a segmental or crescent-shaped notch 10. And extending from the rear end of the side 1 is a tooth 11.

After the sheet-metal body has been cut into the form shown in Fig. 2, it is then bent into the shape shown in Figs. 1, 4, 5, 6 and 8, as follows:

The central portion 3 is bent longitudinally into tubular form, whereby the sides 1 and 2 are brought flat together.

The flanges 4 and 5 are then bent outwardly, directly opposite to each other, and at right-angles to their respective sides 1 and 2.

The teeth 7, 8 and 11, extending from the side 1, are then bent over and into contact with the face of the side 2, thereby securing the sides in position and preventing them from springing apart.

The tongue 6 is then bent outward, bringing it at an angle with relation to the side 1, substantially as shown in the drawings.

The sides of the tongue 9 are then curved toward each other, in order to make the under side of the tongue 9 rounding, as shown in Fig. 5 whereby it will make a smooth contact with the edge of the frame.

The forward outer corners of the sides 1 and 2 are then bent outward, opposite to each other, forming the wings 12 and 13, bending them on the respective dotted lines y and z.

Numeral 14 denotes the clamp, or clamping-member, which is of tubular shape, with its edges approaching each other.

Said member 14 is adapted to slide over the smaller ends of the flanges 4 and 5, and as the member 14 is forced toward the larger ends of said flanges it is evident that 5 the sides 1 and 2 will be securely clamped together.

Letter G denotes a cutting blade, which is placed between the sides 1 and 2, with a portion of the edge of said blade exposed in the 10 notch 10, as shown in Fig. 5. Said blade can be removed or replaced by simply removing the member 14 to release the lower edges of the sides between which said blade is disposed.

15 The stem, shown alone in Fig. 3, comprises a straight central portion 15, which is round in cross-section, and it is of such size as to fit snugly in the tubular central portion 3. One end of the stem terminates 20 in a sharp point 16, while its other end terminates in a ring 17 which forms a handle.

In practice the glass, picture, and stiff backing is first secured in the frame A in 25 the usual manner. A sheet of paper is then pasted over the backing and the back of the frame, in order to exclude dust, smoke, and moisture, and this paper projects out beyond the frame, usually at all four edges of the 30 frame. My tool is then brought into action by resting the guide-tongue 6 on the sealed paper B, with the rounded tongue 9 at substantially right angles thereto and contacting with the outer edge of the frame, thus bringing the juncture of the back of 35 the frame and the outer edge thereof into the notch 10, and thereby bringing the blade G into shearing contact with the frame. Therefore if the tool be grasped in one's hand 40 and drawn along the edge of the frame it will cut the paper along the edge of the frame, regardless of the contour of the frame, thereby forming a smooth and perfect job.

45 After the surplus paper D has been cut away from that attached to the frame it is

evident that what remains is the permanent part B, which latter extends only to the edges of the frame, as indicated in the foreground in Fig. 1.

50 In the next operation the tool is grasped in one's hand and the point 16 is forced into the back of the frame to provide holes in which screw-eyes may be started, said screw-eyes being for the purpose of securing the 55 ends of a cord, wire, or chain by which the frame may be suspended upon a wall. After a screw-eye is started in the hole therefor, then the pointed end of the stem is inserted in the eye of the screw-eye, after which the 60 operator's finger is placed in the ring 17 and then by rotating the stem around, with the screw-eye as the center of rotation, the screw-eye will be driven in to the depth desired, which will complete the operation. 65

I desire that it be understood that various changes may be made in the several details herein set forth without departing from the spirit of the invention and without sacrificing any of the advantages thereof which are 70 new and useful.

Having now fully shown and described my invention, what I claim, and desire to secure by Letters Patent of the United States, is—

75 A tool comprising a body including two sides, a tubular portion formed at the juncture of the two sides and adapted to hold a stem removably therein, a blade located between the two sides, a clamp for detachably securing the blade in position, a tongue disposed at an angle from the corner of one of said sides, a second tongue extending from the corresponding corner of the other side, said tongues being located at right-angles to 80 each other, there being a notch formed in the body between said tongues to expose a portion of said blade.

85 In testimony whereof I have hereunto subscribed my name to this specification.

CLARK H. RUTTER.
